CLAIM

The ornamental design for a stylus, as shown and described.

DESCRIPTION

FIG. 1 is a perspective view of a stylus showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is a cross-sectional view taken along line 9-9 in FIG. 3; and,

FIG. 10 is an enlarged cross-sectional view taken along line 10-10 in FIG. 3.

The broken lines illustrate portions of the stylus that form no part of the claimed design.

1 Claim, 9 Drawing Sheets
